SECONDARY PRESELECTOR

Fernand P. Gohorel, Paris, France, assignor to
 International Standard Electric Corporation,
 New York, N. Y., a corporation of Delaware

Application February 14, 1947, Serial No. 728,633
 In France May 5, 1946

17 Claims. (Cl. 179—18)

1

This invention relates to new and useful improvements in call-distributing arrangements for machine switching, e. g. telephone exchanges.

It is known that the distribution capacity of a group of lines outgoing from a selector having a limited number of outlets can be increased by providing an intermediate non-numerical switch, a so-called "secondary" preselector, arranged to extend each of the outlets of the selector to a different group of lines.

In order to reduce the selection time, preselectors have been positioned on an idle line and moved when this line was seized by another preselector. However, this necessitates the frequent and unnecessary operation of the secondary preselectors even during periods of light traffic, and results in premature wearing out of the preselectors.

The object of the present invention is to lessen the operation of the preselectors while still retaining the advantage of preselection.

One of the features of the invention consists in an arrangement of the circuits of the preselectors and in such grouping of the preselectors that they will be operated only when all preselectors connected to the terminals of a group of selectors are standing on terminals of busy lines.

Another feature of the invention consists, in combination with the above arrangement, of means for preventing the moving of the preselectors when all the lines to which they have access are busy.

Another feature of the invention consists, in combination with one and/or the other of the above features, to arrange the lines connected to the preselectors in pairs and to make it possible artificially to make busy the preselector standing on one of the lines when the other is selected and made busy.

In certain cases it may be desirable, and the present invention contemplates the provision of means, to move the preselectors of a group of selectors before all the lines to which they have access are busy, because a call may be initiated before a preselector reaches an idle line.

Another feature of the invention consists of the means necessary for the moving of the preselectors when only a certain number of idle lines remains accessible, without operating the selectors connected to the outlets of the respective group of preselectors.

Various other features will appear from the following description given as an example without limitation, and with reference to the appended drawings, in which:

2

Fig. 1 shows the general layout of an arrangement of the preselectors according to the invention;

Fig. 2 shows a circuit diagram that makes it possible to obtain the desired result;

Fig. 3 is a variant of Fig. 2 and is applicable to the case in which several outgoing lines can be temporarily associated with a common element; and

10 Fig. 4 illustrates the starting circuits for operating preselectors when only one or two idle trunks remain accessible, without starting the selectors connected to the outlets of the respective preselectors.

15 Fig. 1 illustrates two groups of selectors S_1, S'_1 , and S_2, S'_2 , each having n outlets (five in the example shown), and five groups of preselectors $P_1, P'_1, P_2, P'_2 \dots P_5, P'_5$, each having access to p lines. Trunk connections between the terminals of the selectors and the wipers of the preselectors are made in accordance with well known arrangements in such a way that each outlet of a group of selectors is connected to a preselector that has access to different lines; each selector 20 can accordingly have access to np lines.

25 A suitable device C_1 prevents preselectors P_1, P_2, P_3, P_4, P_5 , which serve the first group of selectors, from starting to hunt for an idle line unless the lines on which they are waiting are all 30 busy. During this time a selector of the first group S_1, S'_1 immediately can have access to an idle line over one of preselectors P_1 to P_5 , and it is not necessary to set in motion any preselector. The same holds good for preselectors P'_1 to P'_5 that serve the second group of selectors S_2, S'_2 .

35 In Fig. 2 the relay contacts that are closed when the relay with which they are associated is energized, are designated by the letter T placed 40 in front of the number of the spring, and the relay contacts that are closed when the relay is not energized, by the letter R placed in front of the number of the spring. Furthermore, the contact springs associated with a certain relay are designated by one of the numerals 1 to 9 placed after the reference number of the relay.

45 It will first be assumed that the wipers of preselector P (Fig. 2) are standing on the terminals of an idle line; the idle potential is applied to bank contact TS of the selector S over wiper TP of the preselector and a resistance Re_1 individual to the idle line. Relay 5 becomes energized across resistance Re_1 , and closes at $T5$ the energizing circuit of relay 6 .

50 When a selector hunts for an idle trunk, its wipers stop on one leading to said preselector,

and ground (not shown) is applied to the selector bank contact AS, which energizes relay 2 over R22. Relay 5 falls back, being short-circuited by ground applied by the selector wiper over bank contact TS, but relay 6, being multiplied to the T51 contacts of all the lines to which the preselector in question gives access, remains in the operating position as long as one of the relays 5 is energized, i. e. if said lines are not all busy.

Relay 2 then locks up over: battery, left-hand winding of 2, T24, bank contact TS, and ground applied by the selector. The connection of the selector to the line is effected by contacts T22 and T24. At R23, relay 2 cuts out relay 3; and at T23 it completes the following circuit: battery, resistance, Re₂, T23, wiper RP and bank contact, wire rp multiplied to the bank contacts of all the preselectors of the same group, and in all the preselectors of said group that are available and stopped on the same line, bank contact and wiper RP, R23, relay 3, contact r1 associated with R, battery.

Relays 3 of these preselectors become energized.

If, among all the preselectors that serve the group of selectors in question, there is at least one available that is standing on an idle line, i. e. on a line other than the one just seized by preselector P, relays 2 and 3 of this preselector are in the resting position, and nothing happens.

On the other hand, if all the preselectors that serve the group of selectors in question are either busy or standing on a line previously seized by another preselector, one of the relays 2 or 3 is pulled up in each preselector; relay 2 if the preselector is busy, and relay 3 if the preselector is standing on a busy line.

The device C1 or C2 of Fig. 1 which prevents the preselectors from starting to hunt for an idle line unless the lines on which they are riding are all busy, consists in Fig. 2 of the three wires a, b, and c of the preselectors serving the same group of selectors such as S1, S'1 of Fig. 1. As shown in Fig. 2, wires a, b, and c are part of preselector P1, a', b', and c' are part of preselector P2 and a'', b'', and c'' are part of preselector P3 of Fig. 1. A ground is then applied to wire c over the following circuit: wire a, contact T25 of the preselector P that has just been seized by the selector, wire b, and, in a second preselector serving the group of selectors in question, wire a', T25' or T31', wire b', and in a third preselector of the group, wire a'', T25'' or T31'', wire b'', operating contacts of one of the relays 2 or 3 of all the other preselectors of the group, to wire c. This wire c is connected to the contacts 32, 32', 32'' of all the preselectors of this group, whereby at this moment all the relays 4 are operated in the preselectors that have their relays 3 energized, i. e. that are available and stopped on a busy line. In each of these preselectors, relay 4 remains energized over T33 and T41 and closes the circuit of magnet R over: ground, T42, magnet R, point g, T61, battery. The magnet opens at r1 the circuit of relay 3. Relay 4 falls back, since the circuit of its two windings is opened at T32 and T33, respectively, and opens at T42 the circuit of magnet R, which releases its armature and causes the advance of the preselector's wipers to the next position.

The cycle is repeated if the new line at which the preselector wipers arrive is busy and if the lines at which the other preselectors of the same group happen to be standing are also busy.

As long as there are idle lines accessible to a group of preselectors, relays 5 of those lines are energized.

Relay 6, which is grounded over contacts T51 in parallel with all relays 5, becomes energized, and battery is applied to point g and, thus, to magnets R. When there is no longer any idle line, all the relays 5 are in the resting position, being short-circuited by the ground applied via the wipers TP, opening at T51 the circuit of relay 6, which falls back and prevents the advance of the preselectors that have access to this group of lines.

The variant of Fig. 3 shows two lines L₁ and L₂ multiplied by wires M₁ and M₂ to all the preselectors of the same group. Relays 7 and 8 correspond to relay 2 of Fig. 2, relay 7 being connected to line 1 and relay 8 being connected to line 2, these relays operating when the line is seized similarly to the way relay 2 of Fig. 2 operates. In the resting position, idle potential is applied to the two lines over contacts 72 and 82 of relays 7 and 8, respectively associated with each line. When one of these lines becomes busy, e. g. line L₁, the busy ground applied by wiper TP of the preselector to bank contact t₁ of line L₁ reaches also bank contact t₂ of line L₂ across contacts R72 and R82. Line L₂ is thus artificially marked busy on the banks of the preselectors.

When a preselector stops on line L₂, the following circuit is completed: battery applied to wiper RP in the manner mentioned for Fig. 2, bank contact r₁, R71, R81, bank contact r₂, and ground across relay 3 of the preselector standing on line L₂. From the above explanations it can be seen that if there is no longer any idle line accessible for the preselectors, the preselector that is standing on line L₂ will advance by one step; from the standpoint of the operation of the preselector, the two lines behave as if they were a single line.

When the connection of the preselector to the line L₁ is completed, relay 7 associated with line L₁ becomes energized, opens its contacts R71 and R72, dissociating the two lines, and thus permitting line L₂ to operate independently of line L₁. Line L₂ can be marked available on the bank contacts of the preselectors independently of the condition of line L₁, and the advance of a preselector standing on line L₂ is no longer dependent on what happens on line L₁.

In order to reduce operations to a minimum, it is advisable that the lines associated with the same common element should not be disposed consecutively in the bank of the preselectors.

The circuit of Fig. 4 shows a variant of the circuit of Fig. 2, in that the hunting of the idle preselectors is started when less than all of the outgoing lines are busy. The relay 4 shown in Fig. 4 is the same relay 4 shown in Fig. 2. The variant of Fig. 4 shows only the circuits for controlling the starting of the preselectors. The chain circuit of Fig. 2 (wires ab, a'b', a''b'') is replaced by a circuit that terminates in a double wound relay 9. Contacts 25, 31, 25', 31', 25'', 31'', etc. are shunted by equal resistances r, r', r'', etc. Relay 9 is so designed that the fluxes produced by the right-hand winding and the bottom left-hand winding pull up armature 91 when the flux produced by the top left-hand winding is not high enough to counterbalance the flux produced by the bottom left-hand winding. If it is desired to start when only a single line remains idle, the top left-hand winding is designed so that the flux it produces is equal to that produced by the bottom left-hand winding when the resistance of the chain circuit is reduced to the value r; if the start is to be effected when two accessible idle lines remain, the top left-hand

winding is designed so that the flux that it produces is equal to that produced by the bottom left-hand winding when the resistance of the chain circuit is equal to $2r$.

Relay 9 is polarized by the right-hand coil in such a way that, if the resistance of the chain falls below the equilibrium value (i. e. 0 or r in the two above cases), the armature is not pulled up again by the resultant reverse flux.

What I claim is:

1. In a telephone exchange system, a plurality of incoming lines terminating in first switches, a plurality of second switches, outgoing lines selected by the second switches, means for rendering said outgoing lines busy, trunks connecting the first to the second switches, magnets for operating the first and second switches, means for rendering an idle second switch busy when said second switch has selected an outgoing line that becomes busy and a chain circuit controlled by said last mentioned means for operating the magnets of idle second switches only when a predetermined number of the idle second switches has selected busy lines.

2. The system according to claim 1, and in which said predetermined number includes all the secondary switches which have selected busy outgoing lines.

3. The system according to claim 1, including means for preventing the operation of the magnets when all the outgoing lines are busy.

4. The system according to claim 1, including means for preventing the operation of the magnets when a predetermined number of said outgoing lines is busy.

5. The system according to claim 1, and further comprising two relays in each second switch, means for energizing the first of said relays when the associated second switch is taken into use by a first switch, means for energizing the second of said relays when the outgoing line selected by an idle second switch is busy, the chain circuit including contacts of said second relays, and energizing circuits for the magnets of all said second switches controlled by all the second relays.

6. The system according to claim 1, and further comprising two relays in each second switch, means for energizing the first of said relays when the associated second switch is taken into use by a first switch, means for energizing the second of said relays when the outgoing line selected by an idle second switch becomes busy, the chain circuit including contacts of said two relays, and energizing circuits for all the magnets of the second switches controlled by all the second relays and one first relay.

7. In a telephone exchange system, a plurality of groups of selectors, each having a multipled terminal bank and wipers cooperating therewith, incoming lines terminating in said wipers, a plurality of groups of preselectors, each having a multipled terminal bank and wipers normally positioned on idle terminals, outgoing lines terminating in the preselector bank terminals, means in each preselector responsive to a busy outgoing line, trunks connecting the banks of one group of selectors to the wipers of different groups of preselectors, each preselector having a magnet for moving its wipers onto terminals of idle called lines, and means controlled by said busy-line-responsive means for operating the magnets of a group of idle preselectors only when the wipers of a predetermined number of the preselectors of the group are standing on busy lines.

8. The system according to claim 7, and in which the predetermined number includes all.

9. The system according to claim 7, and further comprising means for preventing the operation of the magnets of a group of idle preselectors when all the outgoing lines in their banks are busy.

10. The system according to claim 7, and further comprising means for preventing the operation of the magnets of a group of idle preselectors when a predetermined number of outgoing lines in their banks are busy.

11. The system according to claim 7, and further comprising two relays in each preselector, means for energizing the first of said relays when the preselector is taken into use by a selector, means for energizing the second of said relays when the outgoing line on which an idle preselector is standing is busy, and energizing circuits for the magnets of all idle preselectors belonging to the same group controlled by the second relays of all idle preselectors of the group.

12. The system according to claim 7, and further comprising two relays in each preselector, means for energizing the first of said relays when the preselector is taken into use by a selector, means for energizing the second of said relays when the outgoing line on which an idle preselector is standing is busy, and energizing circuits for the magnets of all idle preselectors belonging to the same group controlled by the second relays of all idle preselectors of the group and the first relay of one.

13. The system according to claim 7, and further comprising two relays in each preselector, means for energizing the first of said relays when the preselector is taken into use by a selector, means for energizing the second of said relays when the outgoing line on which an idle preselector is standing is busy, energizing circuits for the magnets of all idle preselectors belonging to the same group controlled by the second relays of all idle preselectors of the group and the first relay of one, and means for preventing the closure of said energizing circuits when all the outgoing lines are busy which terminate in the preselector banks.

14. In a telephone system, a plurality of incoming lines terminating in first switches, second switches, magnets for operating the first and second switches, trunks connecting the first to the second switches, outgoing lines selected by the second switches and arranged in pairs, means for rendering the second one of the pair of lines busy to the first switches when the first line of the pair is selected by a second switch, and means for removing the busy condition from the first line of the pair when the connection with the second line of the pair has been established.

15. In a telephone system, a plurality of selectors, each having a multipled terminal bank and wiper cooperating therewith, incoming lines terminating in said wipers, a plurality of preselectors, each having a multipled terminal bank and wipers normally positioned on idle terminals, trunks connecting the wipers of said preselectors with terminals of said selectors, outgoing lines terminating in the preselector banks and arranged in pairs, means for rendering the second outgoing line of the pair busy to the selectors when the preselector selects the first outgoing line of the pair, and means for removing the busy condition from the second outgoing line when the preselector has made connection with the first outgoing

75 line.

16. In a telephone system, a plurality of incoming lines terminating in first switches, a plurality of second switches, magnets for operating the first and second switches, trunks connecting the first to the second switches, outgoing lines selected by the second switches, means for rendering an idle second switch busy to the first switches when it has selected a busy outgoing line, means for operating the magnets of the idle second switches only when a predetermined number of idle second switches have selected busy outgoing lines, and relay means common to the outgoing lines for preventing the operation of the magnets of idle second switches when all the outgoing lines are busy.

17. In a telephone system, a plurality of incoming lines terminating in selectors, a plurality of preselectors adapted for selection by the selectors, trunks connecting the terminals of the selectors with the wipers of the preselectors, magnets, wipers and terminal banks for the selectors and the preselectors, outgoing lines adapted to be

selected by the preselectors, an idle preselector being busy to the selectors when the wipers of the idle preselector are resting on the bank terminals of a busy outgoing line, means for operating the magnets of idle preselectors only when the wipers of a predetermined number of idle preselectors are resting on busy outgoing lines, and relay means common to the outgoing lines for preventing the operation of the magnets of idle second switches when all the outgoing lines are busy.
